United States Patent Office

Des. 211,515
Patented June 25, 1968

211,515

AMPHITHEATER

Frederick I. Goldberg, 1625 Emmons Ave., Brooklyn,
N.Y. 11235, and Robert Colwell Petrucelli, 228 New
Hanover Ave., Meriden, Conn. 06450

Filed Mar. 4, 1966, Ser. No. 1,410

Term of patent 14 years

(Cl. D13—1)

Des. 211,515

PAGE 2

T1-2.

FIG. 1 is a perspective end view from above of an amphitheater according to our invention;

FIG. 2 is a perspective end view from above, as seen from the end opposite to that shown in FIG. 1;

FIG. 3 is a perspective side-end view from above, showing further features of our invention; and

FIG. 4 is another fragmentary perspective side-end view seen from above.

We claim:

The ornamental design for an amphitheater, substantially as shown.
